UNITED STATES PATENT OFFICE.

WILLIAM A. WITHERS, OF ELIZABETHTOWN, PENNSYLVANIA, ASSIGNOR TO W. A. WITHERS SHOE COMPANY, OF ELIZABETHTOWN, PENNSYLVANIA, A CORPORATION OF PENNSYLVANIA.

METHOD OF MANUFACTURING SHOES.

Application filed February 11, 1924. Serial No. 691,885.

To all whom it may concern:

Be it known that I, WILLIAM A. WITHERS, a citizen of the United States, residing at Elizabethtown, in the county of Lancaster and State of Pennsylvania, have invented a new and Improved Method of Manufacturing Shoes, of which the following is a specification.

My invention relates to shoes and to methods of making the same.

One object of my invention is to provide a shoe that shall be free from lasting cords or tacks.

Another object of my invention is to provide a shoe that shall have the adjacent surfaces of the soles free from the unevenness caused by the presence of lasting cords or tacks.

It is also an object of my invention to provide an improved method of manufacture of shoes.

It is still another object of my invention to provide a method of manufacturing shoes characterized by permitting moist leather to dry into its final shape, thereby eliminating the use of permanent lasting cords or tacks.

It is a further object of my invention to provide a method of making shoes, steps in which consist of drawing a moist welt into position over an insole and then permitting the welt to dry in place after which it remains in position without the aid of lasting cords or tacks.

In the accompanying drawings,

Figure 1 is an elevational view, of a shoe upper and welt sewed in their initial position;

Figure 2 is a plan view of the inner sole and attached welt and upper;

Figure 3 is a view, partially in section and partially in elevation, of the parts shown in Figure 2, fitted upon a forming last;

Figure 4 is a similar view of a shoe in an intermediate step in its assembly of the shoe, and

Figure 5 is a similar view of a completed shoe.

My invention consists, in general, of sewing a moistened welt to an assembled shoe upper, turning the welt over the outer face of the inner sole, retaining the welt in this position until it becomes dried, gluing an outer sole to the assembled inner sole and welt, trimming the assembled welt and outer

sole, and then sewing the outer sole to the 55 welt.

Referring to Fig. 1, there is shown a shoe upper 11, comprising a plurality of sections 12, 13 and 14 that are suitably fastened together, as by sewing, the section 14 being 60 provided with suitable eyes 15 for the reception of lacings, (not shown). These parts may be of any conventional form as they form no part of my invention except in so far as they are necessary to complete the 65 combination of parts and the method of manufacture hereinafter described.

The lower edge of a moistened welt 16 is sewed to the lower edge of the upper 11, the upper edge of the welt 16 being left free 70 from the upper 11. The upper 11 is then placed over a last 17 and an inner sole 18 is placed over the bottom face of the last 17 and inside of the upper 11.

Referring to Figs. 2 and 3, the lower edge 75 of the upper 11 and the attached welt 16 are then forced over the outer edge of the inner sole 18 and secured by lasting tacks 19. Lasting cords may be used in lieu of the tacks 19 if desired, as they are equivalent fastening means.

The shoe is then permitted to remain in this condition until the welt 16 becomes dried and assumes a permanent shape. The outer edge of the welt 16 assumes a position 85 substantially in the plane of the inner sole 18 and at right angles to the adjacent undeformed portion of the upper 11.

The tacks 19 are thereupon removed, or the lasting cords are removed, if employed. 90 The shoe is then held in the assembled position on the last 17 only by the resistance to bending of the welt 16. The shoe is now free from tacks or lasting cords that might cause unevenness of the inner sole of the 95 finished shoe in service.

A layer of adhesive 21, such as paste or mucilage, is then spread over the exposed surfaces of the welt 16 and the inner sole 18. As shown in Fig. 4, the outer sole 22 100 is then pressed upon the prepared surface and is held there by the adhesive 21. A cork filler is inserted if desired.

The sole 22 is held in this manner during the trimming operations, after which it 105 is stitched, as at 23, in Fig. 5, to the extending portion of the welt 16. The surface of the sole 22 is then rolled in order

2
to force the stitches 23 beneath the wearing surface thereof.

The term "moistened welt" is intended to include the use of a welt strip in contact with a dampened upper or the wetting of both the welt and upper by any process such as dipping.

Accordingly, I have provided a method of making shoes that is characterized by 10 drawing the edge of a shoe upper and an attached moistened welt over an inner sole, temporarily securing these parts in place until the welt dries, and then making use of the resistance to change of shape offered 15 by the dried welt for holding the parts together during subsequent operations in the manufacturing of the shoes. I also trim the outer sole while it is held to the assembled shoe only by a layer of adhesive 20 and before the final securing stitches are sewed through the outer sole and the welt.

Various changes and modifications may be made in the details and arrangements of my invention without departing from the 25 spirit and scope thereof, as set forth in the appended claims.

I claim as my invention:

1. A method of making shoes that includes sewing an edge of a moistened welt 30 to an edge of a shoe upper, drawing the attached edges of the upper and welt over the edge of an inner sole and temporarily securing them thereto, permitting the welt to dry, removing the temporary securing 35 means, utilizing the resistance to change of shape offered by the dried welt for holding

the assembled shoe in shape, preparing the exposed area of the inner sole and welt, and then securing an outer sole thereto.

2. A method of making shoes that includes sewing an edge of a moistened welt to an edge of a shoe upper, drawing the attached edges of the upper and welt over the edge of an inner sole and temporarily securing them thereto, permitting the welt to dry, removing the temporary securing means, utilizing the resistance to change of shape offered by the dried welt for holding the assembled area of the inner sole and welt, covering the exposed surface with an adhesive, placing an outer sole thereon, trimming said outer sole, and then sewing said outer sole to the other edge of the welt.

3. A method of making shoes that includes attaching an edge of a welt to an edge of a shoe upper, the welt being moistened, drawing the attached edges of the upper and welt over the edge of an inner sole and temporarily securing them thereto, permitting the welt to dry, removing the temporary securing means, and then utilizing the resistance to change of shape offered by the dried welt for holding the assembled shoe in shape during a subsequent operation.

4. A method of making shoes that includes placing a moistened welt over an inner sole, holding the moistened welt in position until it becomes dry, and then utilizing the resistance to change of shape of the dried welt for holding the assembled shoe in shape during subsequent operations.

WM. A. WITHERS.
